Attorney

UNITED STATES PATENT OFFICE.

FRANK VAN ANDEN, OF MIAMI, FLORIDA.

BLOCK-MOLDING DEVICE.

Application filed September 18, 1925. Serial No. 57,120.

To all whom it may concern:

Be it known that I, FRANK VAN ANDEN, a citizen of the United States, and a resident of Miami, county of Dade, and State 5 of Florida, have invented certain new and useful Improvements in Block-Molding Devices, of which the following is a specification.

This invention relates to block molding 10 device having for its primary object to provide means of simplified and improved construction and operation for the production of concrete building blocks or tiles.

A further object is to provide mechanical 15 means whereby concrete blocks or tiles may be molded and in which operation the exposed surfaces or walls of the blocks or tiles are glazed or surfaced in a manner similar to troweling operations.

20 A further object is to provide a mold box, pallet and tamper of improved construction, as more fully hereinafter will appear, for the production of building blocks or tiles of the character above described.

25 With these objects in view, together with others which will appear as the description proceeds, the invention consists in the novel construction, combination and arrangements of parts, all as will be described more fully 30 hereinafter, illustrated in the drawings and particularly pointed out in the claims.

In the drawings:

Fig. 1 is a perspective view of a tamper embodying the invention,

35 Fig. 2 is a similar view of the mold box showing the cores arranged therein,

Fig. 3 is a perspective view of the pallet removed from the box,

40 Fig. 4 is a transverse sectional view taken through the pallet,

Fig. 5 is a similar view taken longitudinally through the pallet.

45 Fig. 6 is a longitudinal sectional view taken through the mold box, tamper and pallet illustrating the assemblage of these elements and showing therein a block partly formed,

Fig. 7 is a transverse sectional view taken 50 through the structure represented in Fig. 6,

Fig. 8 is a perspective view of a modified form of a tamper,

Fig. 9 is a bottom view of the tamper shown in Fig. 8, and

Fig. 10 is a perspective view of a cement block produced by the improved molding 55 device.

It is well known that troweling operations upon concrete, cement or similar materials produces a film, coating, or shell which hardens or "sets" into a protective water 60 proof or water resisting covering or coating which is highly desirable. It has heretofore been found impossible to produce such a coating or shell in block molding or wall forming processes without the manual troweling operation, and it is an important object of the present invention to mechanically 65 form blocks or tiles with this shell or coating effect without resorting to the manual troweling operation.

70 It is furthermore contemplated to simplify the construction of the several mold parts so that the same may be effectively used at a great economy of time as well as at a saving of material and manual labor. 75 Such results are accomplished by the means and operations now to be more fully set forth.

The mold in the present instance is designed for the production of hollow blocks 80 or tiles of rectangular formation, and comprises a box represented generally at 11. This box will be of the desired length and breadth and is open at its top and bottom. The mold box is provided with any desired 85 number of cores 12, two being shown in the present instance. These cores are of suitable size, and it is important that the side walls thereof be parallel and evenly spaced from the walls of the mold box and from 90 each other.

Associated with the mold box is a pallet 95 13. This pallet is of a size conforming to the length and breadth of the mold box, and is to be inserted in the latter; suitable small clearance being allowed for convenience in insertion and removal of the pallet. The side and end bars of the pallet are of a breadth substantially equal to the distance between the inner surfaces of the box walls 100 and the adjacent faces of the cores, so that openings 14 are provided in the pallet of a size to properly accommodate the cores.

105 The side and end bars of the pallet are of such construction that the upper faces thereof correspond to the width of the mold

2

channels, but the lower or supporting edges thereof are of restricted breadth. This is so that the pallet may cut its way through the matter, such as soft cement or other 5 plastic which may have accumulated upon the mold support, to insure firm setting and proper levelling of the pallet. In the present instance, therefore, the side and end bars of the pallet are of triangular shape in cross- 10 section, with the bases of the triangles disposed uppermost. This causes the apexes of the triangles to be disposed downwardly, providing knife edges 15. While this is the preferred formation of the pallet bars, it is 15 obvious that slight variations therein may be effectively employed. The triangular construction, furthermore, produces acute angles where the sides of the triangles join the base, whereby knife edges are thus produced. Such edges enable stiff cement and other matter accumulated thereon to be effectively removed by simplified methods and at a great saving of time and labor, and in practice it has been found that such matter 20 is cleared from the pallet edges in the inserting operation.

One form of tamper for use in the production of concrete blocks or tiles is shown in Fig. 1. This tamper, 16 conforms to the 30 shape and arrangement of the channels within the mold so as to snugly fit therein, and is equipped with an operating standard or handle indicated at 17.

In operation, the carrier 18, is placed 35 within the mold box, whereupon the pallet is inserted and rests upon the carrier. The cores protrude through the openings 14 of the pallet, as will be understood. The plastic mixture is then poured into the channels 40 of the mold and the tamper is operated to firmly press the same down into the channels. This is carried out by vertical reciprocations or poundings of the tamper in the usual manner. When the mold has been 45 filled and the tamping operation has firmly pressed the cement mixture against the walls of the mold box and cores, the stripping operation is carried out. The stripping is the operation of pushing the completed 50 block or tile out of the mold box, and by reason of the firm contact of the plastic mixture with the smooth walls of the mold box and cores, the smoothing off or troweling operation upon the exterior and interior 55 walls of the block or tile is performed. By reason of the fact that a high degree of 60 pressure is maintained upon the plastic matter within the mold during its operation of stripping, and as this pressure continues due to the core and mold walls being parallel with each other throughout the stripping operation, the outer and inner surfaces of the 65 block or tile are smoothed off so as to form the highly desirable shell or coating heretofore accomplished only by manual trowel-

ing. It is important that the mold and core walls be parallel, so that the troweling or smoothing off effect may be produced throughout the entire stripping operation. In this stripping operation, upward pressure 70 is applied to the carrier 18, whereby the pallet and carrier travel upwardly to strip the block or tile from the mold box at the same time high degree of pressure is maintained 75 upon the plastic material.

A modified and improved form of tamper is shown in Fig. 8, wherein the same is formed in three sections, 19, 20 and 21. These sections, when assembled, correspond substantially to the layout of the mold channels and each is equipped with an operating bar or rod 17. This tamper is operated so that the sections thereof work alternately, to cause a more even distribution of the plastic mixture within the mold and to tightly 80 compress the plastic mixture against the walls of the box and the cores. By the use of such a tamper, it is obvious that regardless of where the bulk of plastic mixture is placed within the mold, it will be evened out 85 and properly distributed in the alternate operations of the several tamper sections.

In Fig. 10 there is illustrated a block produced by a mold device in accordance with the invention. Such blocks may be laid on top of each other, in alternate relation or side by side. In instances where it is advisable to tie the blocks together with iron or steel bars, the edges of the blocks may be recessed as represented at 22, for the accommodation of such tie rods. Grouting 90 may be poured into the openings in the assembled blocks to anchor them to the foundation and to each other.

It has been found that blocks or tiles constructed in accordance with my method and apparatus may be made with walls considerably thinner than in blocks of like nature produced by other operations. Thus it will be seen that my blocks or tiles are produced at a great saving of material, and blocks of comparatively light weight yet capable of withstanding great pressures are provided. The increased degree of strength inherent in blocks of my construction is due to the "skin" or coating effect upon both the interior and exterior surfaces of the blocks or tiles. When such coating has become "set" or hardened, great rigidity is 105 present in the block.

From the foregoing it is apparent that I have provided a concrete block apparatus and method of extremely simple construction and yet which will effectively operate in the accomplishment of the several objects set forth. While the foregoing is a description of the invention in its preferred embodiment, it is nevertheless understood that variations in the size, shape and proportion 110 of the parts, as well as the details of con- 115

struction thereof, may be liberally resorted to without departing from the spirit of the invention as defined by the claims.

Having thus described my invention, I 5 claim:

1. In a device of the class described, a mold box, a pallet removably arranged in said box, cores protruding through said pallet, the edges of said pallet engaging said 10 box and cores presenting acute angles, and a knife edge supporting said pallet.

2. In a device of the class described, a pallet for mold boxes comprising a plate corresponding in size and shape with the interior of said box, the said plate having core 15 openings therein, the portions of said plate engaging said box and the cores comprising knife edges, and a relatively sharp rib depending from said plate and supporting the 20 latter.

3. In a device of the class described, a pallet for mold boxes comprising a plate corresponding in size and shape with the interior of the box, said plate having core

openings, and the several portions of said 25 plate being triangular in cross-section with the bases of the triangles disposed uppermost.

4. In a device of the class described, a mold box, cores in said box, a sectional 30 tamper, the assembled section of said tamper corresponding with the shape and size of the channels between said cores and box, and the said sections adapted to be operated alternately.

5. In a device of the class described, a mold box open at its top and bottom, a pallet removably engaged in the bottom of said box, cores in said box protruding through said pallet and spaced from the walls of 40 said box, and a sectional tamper, the assembled sections of said tamper conforming to the spaces between said cores and box and adapted to be operated alternately.

In testimony whereof I affix my signature.

FRANK VAN ANDEN.
